ASSIGNORS TO THE MARLIN FIREARMS COMPANY, OF NEW HAVEN, CONNECTICUT,
A CORPORATION OF CONNECTICUT.

GUN-SIGHT.

1,150,791.

Specification of Letters Patent. Patented Aug. 17, 1915.

Application filed April 15, 1915. Serial No. 21,558.

To all whom it may concern:

Be it known that we, CARL G. SWEBILIUS and HANS T. R. HANITZ, a citizen of the United States and a subject of the Emperor of Germany, respectively, residing at New Haven, New Haven county, State of Connecticut, have invented certain new and useful Improvements in Gun-Sights, of which the following is a full, clear, and exact description.

Our invention relates to an improved gun sight, the object being to provide simple and effective means for shifting sight both vertically and laterally to effect the necessary adjustment for elevation and windage.

In the accompanying drawings: Figure 1 is a plan view of our sight as it would appear on a rifle barrel and relatively enlarged. Fig. 2 is a cross-section on the line 2—2. Fig. 3 is a section on the line 3—3. Fig. 4 is a perspective view of the sight frame. Fig. 5 is a perspective view of the sight proper detached. Figs. 6 and 7 are conventional views of details.

1 represents part of a rifle barrel upon which the sight is mounted in any suitable manner. In this particular instance, the top of the barrel is provided with an undercut groove to receive the dove-tailed base 2 of the sight frame. The sight proper comprises the part 3 over which the sight is taken. In this instance the sight is taken through a groove 4 in the upper flat surface of the part 3. At one end of the part 3 is a hub 5 upon which is mounted an operating member 6. The member 6 is so mounted on the hub 5 that the latter may slide in, but not rotate independently of the operating member 6. At the other end of the part 3 is a threaded hub 7 upon which is mounted an operating device 8, the latter being threaded on the part 7. At each end of the base 2 of the sight frame are suitable brackets, in this instance in the form of rings 9—9—10—10, which afford bearings for the hub ends 5—7 respectively, the rings 9—9 being spaced properly to afford room for the operating member 6, the rings 10—10 being properly spaced to afford room for the operating member 8.

Suitable means are employed to prevent the operating members 6—8 from accidentally turning out of their adjusted positions. In the preferred form of such means shown

in the drawings, we employ a double-ended 55 spring seated in a suitable groove in the bottom of the base 2, said groove intersecting the space between the rings 9—9 and 10—10, so that the spring ends will frictionally engage the edges of the operating members 6—8, for example, the end 11 of the spring engages the operating member 6, while the end 12 engages the operating member 8. The operating members 6—8 preferably have their outer edges toothed to be 65 more readily engaged and held by the spring ends 11—12. The part 3 of the sight is preferably triangular in cross-section (see dotted lines, Fig. 3), and the sharp edge is preferably slightly notched as at 4^a in line 70 with the groove 4.

We have described the structural features of the sight in their preferred form, but it is obvious that many changes may be made therein without departing from the spirit 75 and scope of the invention.

Operation: When the parts stand as shown in the drawings with the flat grooved surface of the part 3, parallel with the top of the barrel or line of sight, the sight is adjusted for the highest elevation of the gun, assuming the sight shown to be located at the forward end of the barrel. To lower the elevation of the gun the sight is gradually turned by the member 6, thus relatively raising the edge having the sighting notch 4^a until the desired elevation has been secured. This may be increased at will until the lowest elevation is obtained, which occurs when the grooved surface of the sight body 3 stands vertically, that is to say, in a plane at right angles to the axis of the barrel, instead of a plane parallel to the axis of the barrel as shown in the drawings. To adjust the sight for windage, that is to say, to shift the sight laterally so as to make due allowance for a side wind, the operator turns the operating member 8 in the proper direction to shift the sight groove 4 and notch 4^a laterally to the necessary degree. If desired, the notches between the teeth at the edge of each operating member 6—8 may be utilized as gage marks. For example, when the operating device 8 has been turned the distance of one tooth, it may indicate a certain arbitrary degree of change in the elevation of the gun; so also a shifting of the operating member 8 the distance of one

tooth, may indicate a certain arbitrary degree of lateral displacement of the effective part of the sight.

Such a sight may be used on any kind of a gun and may be employed either as a rear sight or a front sight, although usually such sights are employed near the rear of the barrel. The bottom of the notch 4^a, which is, of course, co-incident with the bottom of the longitudinal groove 4 when the latter is provided, constitutes the sighting point, and as that point is eccentric to the axis of the sight body and hubs 5—7, it is clear that this sighting point may be raised, lowered, shifted to the right or left at will to any desired degree between the extreme limits of the device.

What we claim is:

1. A gun sight comprising a main body arranged to rotate on an axis transverse to the barrel of a gun on which it is to be mounted, and also arranged to be moved transversely relatively to said gun barrel, said body having a sighting point located relatively to the axis of rotation of the sight body so that the rotation of said body will relatively elevate and depress said sighting point, with means for rotating said sight body and for shifting the same transversely to the axis of the barrel.

2. A gun sight comprising a frame, a main sight body rotatably mounted in said frame transversely to the line of sight, said body being provided with a sighting point, means for rotating said main body to elevate and to depress said sighting point.

3. A gun sight comprising a frame, a main sight body rotatably mounted in said frame transversely to the line of sight, said body being provided with a sighting point, means for rotating said main body to elevate and to depress said sighting point, and to shift said sighting point laterally relatively to the line of sight.

4. A gun sight comprising a frame, a main sight body rotatably mounted in said frame transversely to the line of sight, said body being provided with a sighting point, means for rotating said main body to ele-

vate and to depress said sighting point and to shift said sighting point laterally relatively to the line of sight, said means comprising two independently movable parts.

5. A gun sight comprising a frame, a main sight body rotatably mounted in said frame transversely to the line of sight, said body being provided with a sighting point, means for rotating said main body to elevate and to depress said sighting point, and to shift said sighting point laterally relatively to the line of sight, said means comprising two independently movable parts, one of said parts being mounted at one end of said sight body, the other part being mounted at the other end of said sight body.

6. A gun sight comprising a supporting frame, a main sight body rotatably mounted at its ends in said frame, the intermediate portion of said body having a notch, the bottom of which forms a sighting point, said sighting point being eccentric to the axis of rotation of the body, with means to rotate said body to elevate and depress said sighting point and with other means to shift said sighting point laterally to the line of sight, without disturbing the elevation of the sighting point.

7. In a sight, a frame including two sets of spaced annular supports at each end, a main sight body having hubs at each end mounted for rotation in said annular supports, an operating device slidably mounted on one hub with means for holding said operating device and hub from independent rotation, said operating device being arranged between the annular supports comprising one set, another operating device mounted to rotate on the other hub and including a threaded connection between said parts, said last mentioned operating device being arranged between the two annular supports constituting the other set, and said body having a sighting point located upon an intermediate part thereof and eccentric to its axis of rotation.

CARL GUSTAF SWEBILIUS.
HANS T. R. HANITZ.
